(57) **CLAIM**

The ornamental design for an electric connector with a cable, as shown and described.

DESCRIPTION

FIG. 1 is a top plan view thereof;

FIG. 2 is a front elevation thereof;

FIG. 3 is a bottom plan view thereof;

FIG. 4 is a rear elevation thereof;

FIG. 5 is a left side elevation thereof; and,

FIG. 6 is a right side elevation thereof.

The claimed design is shown broken away to indicate indeterminate length.

The present design is characterized in that socket members are disposed at opposite cable ends and extend axially of the cable, and in that these members respectively continue to adjacent corrugated parts or portions covering the cable ends.
